UNITED STATES PATENT OFFICE

2,206,176

SCREEN PRINTING APPARATUS

Robert F. Foard, Los Angeles, Calif.

Application March 13, 1939, Serial No. 261,584

9 Claims. (Cl. 101—126)

My invention relates to screen printing apparatus adapted for multiple color printing on cloth and among the objects of my invention are:

First, to provide a multiple color screen printing apparatus whereby particularly accurate registry of the different colors may be readily obtained.

Second, to provide an apparatus of this character which is economical of floor space, the apparatus occupying very little more than twice the area of the material upon which it is capable of printing.

Third, to provide an apparatus of this character which is equally applicable to printing on cut or partially finished articles such as towels, napkins, Table cloths etc.; or to printing on yardage or piece goods in webs or bolts.

Fourth, to provide an apparatus of this character wherein the time requirement in order to apply selected number of colors is reduced to a minimum.

Fifth, to provide an apparatus of this character wherein blended or secondary colors, that is, colors derived from superposed applications of different primary colors may be obtained, by reason of the rapidity of application as well as the accuracy of registry obtained.

Sixth, to provide a simple and novel means for registering the several screens of a multiple color set of screens may be placed upon the goods to be printed in sequence with assurance that the registry once obtained will be maintained.

With the above and other objects in view as may appear hereinafter, reference is directed to the accompanying drawings in which:

Figure 1 is a perspective view of my apparatus.

Figure 2 is a longitudinal sectional view thereof taken substantially through 2—2 of Fig. 1 with one printing frame structure shown partially extended and parts and portions shown in elevation to facilitate the illustration.

Figure 3 is a fragmentary plan view of the printing frame and printing table as they appear when in position for printing.

Figure 4 is an enlarged fragmentary sectional view thereof taken through 4—4 of Fig. 3.

My multiple color screen printing apparatus comprises essentially of a carriage structure 1 adapted to contain a plurality of screen printing frame structures 2 which are capable of being selected and placed one at a time upon a printing table 3.

The carriage structure comprises a housing 11 of rectangular form and having side walls 12, and a bottom 13. The bottom of the housing 11 is suitably mounted on an elevator 14 which may comprise a plunger 15 and cylinder 15a adapted to be actuated by fluid pressure from a suitable source not shown, to raise and lower the housing 11. Suitable uprights 16 may guide the housing

so that it remains level and is restrained to a vertical movement.

The sides 12 of the housing 11 are provided with tracks 17 having a plurality of rollers 18. Also additional rollers 19 may be on the side walls 5 above each track. The tracks are arranged in pairs, each pair adapted to guide and support a screen printing frame structure 2.

Each screen printing frame structure comprises an outer frame 21 preferably formed of angle 10 iron. The sides of the outer frame 21 ride upon and are guided by the rollers 18 and 19. At each rear corner the outer frame 21 is provided with a cam elevator 22 in the form of an upwardly sloping bracket adapted to guide the frame upwardly 15 from the printing table to the corresponding track as will be described in more detail hereinafter.

Within the outer frame 21 is an inner frame 23 which constitutes the printing frame proper. The frame 23 preferably made of wood and is in most respects similar to conventional screen printing frames. The inner or printing frame 23 defines an opening covered by a conventional printing screen 24 of fine grade silk or the like which is treated in such a manner that it is impervious 25 except for those areas through which it is desired to force dye or ink.

The printing frames 23 fit loosely in their outer frames 21 and are secured therein by adjustable wedges or quoins 25 positioned adjacent each corner. Adjustment of the quoins permit adjustment of the printing screen relative to the outer frame to facilitate registry as will be described in more detail hereinafter.

One set of outer frames may be used for several sets of printing frames 23, consequently, in order to facilitate re-registering a printing frame, spacers 26 of fixed thickness approximating the adjusted width of the adjacent quoin are secured to each frame adjacent; thus when a frame 40 has been once adjusted in registry it may be removed from the outer frame and when later replaced therein automatically assumes a position of approximate registry so that further adjustment by means of the quoins is facilitated.

The table 3 includes a table top 31 suitably supported at working height on legs and having a relieved area slightly in excess of the area of a printing frame structure. This area is adapted to receive one of several work holding plates 32 depending on the size and shape of the article to be screen printed. If for example, four articles such as napkins, towels, handkerchiefs or the like are to be printed, four platen faces 33 are provided. Each platen face is defined by channels 34 which connect with each other. The channels extending along the sides from front to rear of the plate extend rearwardly beyond the platen faces to the rear edge of the work holding plate as indicated by 35.

Work is positioned over the platen faces so that its margins extend into the channels 34 and are held therein by a clamping frame 36 which is complementary to said channels including arms

5 37 which extend to the rear edge of the plate and are connected therewith by hinges 38. In addition the front edge of the clamping frame 36 is provided with a hinged handle 39 adapted to hook over the forward edge of the plate and be 10 used to assist in raising the clamping frame.

Both the clamping frame and normal surfaces of the plate 32 including the platen faces 33 are covered with a cushion 40 of uniform thickness.

If a single article is to be printed, the work 15 holding plate is provided with a single platen face the size and shape of which is dependent upon the article in question. It is not necessary that the cloth material be cut to size before printing for yardage may be fed in steps across 20 the table and either one or several prints made thereon at a time. More particularly, adjacent each cam elevator 22 and at the rear edge of the top 31 of the table 3 are provided coacting brackets 41 and 42 including semi-circular, 25 rearwardly directed lip portions 43 and 44 respectively. The lip portion 43 of the bracket 41 associated with the frame structure 2 is provided with a centered aperture 45 and a depending skirt 46; while the lip portion 44 of the other bracket is provided with an upstanding pin 47 adapted to fit the aperture 45.

To facilitate lateral positioning of the frame structure 2, upstanding guide members 48 may be positioned for engagement with the sides of 30 the cam elevators 22.

In addition, to two such coacting brackets at the two rear corners of the frame structure, another set of registering fittings may be provided at one or both outer corners of the frame structure 2.

Thus, brackets 51 and 52 are secured to the frame 21 and table top 31 and are provided with semi-circular lip portions 53 and 54 respectively. The lip portion 53 is provided with a depending 45 pin 55 adapted to fit an aperture in the other lip portion 54, and the lip portion 54 is provided with an upstanding semi-circular guide wall 56.

In order to facilitate removal of the selected frame structure 2 from the carriage 1, an ejector 50 is provided which includes a plunger 61 mounted at the proper height in rear of the carriage and adapted to engage the rear edge of the frame structure positioned in proper relation to the table 3. The plunger 61 is actuated by a 55 lever 62 below the forward side of the table 3 in an accessible position for the operator. A suitable spring, not shown, tends to hold the plunger in a retracted position.

Movement of the plunger is so adjusted that 60 the frame structure is moved only part way out of the carriage so that the forward edge of the frame structure may be grasped by the operator and withdrawn the remaining distance. To facilitate return of the frame structures, the 65 several tracks are on a slight slope downwardly toward the rear of the carriage.

Movement of the carriage may be controlled by a suitable valve 71 which connects the cylinder 15a with a source of pressure fluid, permits 70 bleeding of the pressure fluid from the cylinder or seals the fluid therein so that the carriage may be raised, lowered or stopped.

To facilitate proper positioning of the carriage with respect to the table a stop arm 72 which is 75 hinged to one of the uprights 16 and engages

any one of the track members 47 or other suitable projections on the carriage. The arm 72 is operated by a link 73. A spring 74 tends to hold the arm in an operating position.

Operation of my screen printing apparatus 5 is as follows:

Assuming that four articles are to be printed simultaneously; for example, napkins; these are laid over the platen faces 33 of the plate 32 with their margins in the channels 34. The 10 holding frame is then lowered and the handle 39 thereof used to secure the frame in place by fitting over the edge of the table 3; however, it is preferred to make the holding frame of metal so that its weight alone is sufficient to hold the 15 cloth.

The carriage 1 is then operated to bring a printing frame structure 2 on a level slightly above the table 3. The frame structure is withdrawn, with the assistance of the ejector, the 20 operator holding the front end of the frame structure clear of the work, while the track maintains the rear end of the frame structure clear. The position assumed by the frame structure during such movement is best shown by 25 dotted lines in Fig. 2.

While the front end of the frame structure is held in an elevated position, the cam elevators 22 allow the rear end of the frame structure to descend. The skirts 46 of brackets 41 engage 30 the lips 44 of brackets 42 and guide the pins 47 into place. Sufficient distance is provided between the rear edge of the frame structure and the working area of the screens to insure clearance until the pins 47 are in place. The front end of the frame structure in predetermined registry with the work.

It should be noted that the printing screens 24 are normally spaced upwardly slightly from the work and are forced down into contact with the 40 work by a "squeege" in a conventional manner.

After one color has been applied, the frame structure is returned by first raising the front end until the entire printing screen 24 is clear. This brings the rear end of the elevator cam 22 45 into engagement with the front rollers of the corresponding track whereby the frame structure may be readily returned to the carriage.

The carriage is raised or lowered to position after each operation so that the several frame 50 structures are brought into proper relation. This may be accomplished automatically by any suitable means, not shown, or may be done manually by a valve 71 controlling the fluid in the cylinder 15.

In preparing multiple color designs for printing the design is separated into elements one for each color and applied to the several printing screens in any conventional manner. Approximate registry between the design elements on the 60 screens is easily obtained.

Trial prints are made with the printing screens and each printing screen frame adjusted in its outer frame by means of the quoins 25 until the desired registry is obtained between the different printing screens when the outer frames are held by the coacting fittings between the frame structures 2 and table 3. By use of the spacers 26, it is possible to establish the approximate position of the printing frames 23 so that if it is 70 desired to remove the printing frames so as to print other designs, the printing frames may be replaced without material adjustment.

Though I have shown and described a particular embodiment of my invention, I do not 75

wish to be limited thereto but desire to include in the scope of my invention the constructions, combinations, and arrangements substantially as set forth in the appended claims.

5. I claim:

1. In an apparatus for screen printing on cloth; a table; means for securing thereon cloth to be printed; a plurality of frame structures adapted to fit over said table; coacting fittings 10 on each of said frame structures and table whereby said frame structures may be set interchangeably on said table in predetermined relation therewith; a screen printing frame for each frame structure; adjustable spacer means interposed between each printing frame and its frame structure for adjusting the printing frame into a position of registry over said table corresponding to the registry of the other printing frames and their frame structures when interchange on 15 said table and fixed spacers fitted between each printing frame and its frame structure upon initial adjustment of said adjustable spacers whereby said printing frame may be removed from its frame structure and replaced therein in 20 approximately registry position to minimize re-adjustment of said adjustable spacer means.

2. An apparatus for screen printing on cloth comprising: a table having work receiving platen faces and recesses bordering said platen faces; 30 a clamping frame hinged to said table and adapted to fit in said recesses to hold the marginal portions of cloth overlaying said platen faces, the surfaces of said clamping frame being substantially flush with said platen faces; coacting fittings 35 on each of said frame structures and table whereby said frame structures may be set interchangeably on said table in predetermined relation therewith; a screen printing frame for each frame structure; adjustable spacer means interposed between each printing frame and its frame structure for adjusting the printing frame into a position of registry over said table corresponding to the registry of the other printing frames and their frame structures when interchanged 40 on said table.

3. A structure as set forth in claim 2 wherein fixed spacers approximating the adjusted spacing of said adjustable spacer means are attached to said printing frames after said printing frames have been adjusted into registry, whereby said printing frames may be removed and re-inserted in said frame structures and occupy approximately positions of registry without adjustment.

4. An apparatus for screen printing on cloth comprising: a table; means for securing thereon cloth to be printed; a carriage structure at one side of said table adapted to be raised and lowered; a plurality of screen printing frame structures carried by said carriage and each adapted to be withdrawn therefrom to a position over said table when said carriage is in predetermined relation therewith; and coacting fittings carried by each of said frame structures and said table for mounting each of said frame structures in predetermined relation with said table.

5. An apparatus for screen printing on cloth comprising: a table; means for securing thereon cloth to be printed; a carriage structure at one side of said table adapted to be raised and lowered; a plurality of screen printing frame structures; coacting fittings carried by each of said frame structures and said table whereby said frame structures may be positioned in sequence over said table; a holder for the several screen

printing frame structures adapted to receive the same in superposed, spaced relation; and means for moving said holder to positions whereby a selected frame structure is slightly above the level of the table, whereupon the frame structure may be withdrawn without contact with the table until said fittings are in position for coaction.

6. An apparatus as set forth in claim 5 wherein brackets extend from said frame structures into engagement with said holder to form fulcrum points whereby said frame structures may be moved substantially vertically away from the cloth retained by said securing means.

7. A screen printing apparatus comprising: a table having recesses therein adapted to receive the marginal portions of cloth to be printed; clamp means adapted to fit in said recesses to hold the cloth in position; registering elements on said table; a plurality of screen printing frame structures, each including an outer frame having registering means coacting with said registering elements, an inner frame, means for adjusting and fixing the position of the inner frame with respect to the outer frame, and a printing screen secured to said inner frame; means for supporting said screen printing frame structures in superposed relation on one side of said table; and means for moving said supporting means into positions whereby a selected frame structure may be moved over said table.

8. A screen printing apparatus comprising: a table having recesses therein adapted to receive the marginal portions of cloth to be printed; clamp means adapted to fit in said recesses to hold the cloth in position; registering elements on said table; a plurality of screen printing frame structures, each including an outer frame having registering means coacting with said registering elements; an inner frame, means for adjusting and fixing the position of the inner frame with respect to the outer frame, and a printing screen secured to said inner frame; a carriage for supporting said screen printing frame structures in superposed relation at one side of said table, said carriage including tracks to facilitate withdrawal of said frame structures; means for shifting said carriage to positions whereby a selected frame structure is positioned slightly above the level of said table; and coacting devices on said frame structure and said tracks whereby when a selected frame structure is substantially withdrawn therefrom said frame structure may be moved substantially vertically to or from said table.

9. A screen printing apparatus comprising: a table having recesses therein adapted to receive the marginal portions of cloth to be printed; clamp means adapted to fit in said recesses to hold the cloth in position; registering elements on said table; a plurality of screen printing frame structures, each including an outer frame having registering means coacting with said registering elements; an inner frame, means for adjusting and fixing the position of the inner frame with respect to the outer frame, and a printing screen secured to said inner frame; means for supporting said screen printing frame structures in superposed relation on one side of said table; means for moving said supporting means into positions whereby a selected frame structure may be moved over said table; and an ejector engageable with the selected frame structure for urging the same to a position over said table.

ROBERT F. FOARD.
